UNITED STATES PATENT OFFICE.

CHARLES LORBER, OF LOUISVILLE, KENTUCKY.

KEY CASE.

Application filed April 20, 1926. Serial No. 103,311.

This invention relates to key cases and has special reference to a flexible key case.

One important object of the invention is to provide an improved key case in which 5 the metallic plate common in such devices will be eliminated, the whole structure being of flexible nature.

A second important object of the invention is to provide, in a key case, a flexible 10 unitary bar for supporting the key holding units common in such key cases.

A third important object of the invention is to provide a novel combination of bar and key holding units in such a case.

15 A fourth important object of the invention is to provide a key case of this character wherein selected keys may be positioned selectively on either side of a supporting portion or body and covered, upon 20 closing the case, in said selected positions.

A fifth important object of the invention is to provide an improved form of key case wherein the keys may be selectively positioned with a body, bar holding flap and 25 covers for the front and back made integrally from a suitable piece of flexible material.

With the above and other objects in view 30 as will be hereinafter apparent, the invention consists in general of certain novel details of construction and combinations of parts hereinafter fully described, illustrated in the accompanying drawings and specifically claimed.

35 In the accompanying drawings like characters of reference indicate like parts in the several views, and:

Figure 1 is a front view of one form of the case, certain of the hooks being omitted 40 the better to show the construction of the device.

Figure 2 is a fragmentary view of the device as shown in Figure 1 with the top or bar holding flap folded upwardly as it is when blanking out the main part of the key case.

Figure 3 is an enlarged detail section on the line 3—3 of Figure 1.

Figure 4 is a perspective view of one form 50 of flexible supporting bar used herewith.

Figure 5 is a fragmentary perspective of a second form of supporting bar or rod to an enlarged scale.

55 Figure 6 is a view similar to Figure 5 of a third form of supporting bar.

Figure 7 is a fragmentary perspective of

the upper part of one of the key holding units.

Figure 8 is a perspective view of a modified form of key case having front and back 60 covers and arranged to permit the key holding units to lie on either side of the body of the device, the covers being shown open.

Figure 9 is a view similar to Figure 8 showing both covers closed.

Figure 10 is a view of the modified form showing the bar holding flap upturned.

Figure 11 is an enlarged section on the line 11—11 of Figure 8, the key holding unit being omitted.

Figure 12 is a section on the line 12—12 of Figure 9.

In the first form of the invention there is provided a case having a body portion 10 and cover flaps 11 foldable in overlapping 75 position on the front of the body to close the case and provided with cooperating snap button parts 12 to hold the case closed. At the top of the body is a flap 13 provided with spaced slots 14 and this top flap is 80 folded down on the face of the body and secured near its bottom edge by lines of stitching 15 positioned below the slots 14. There is thus formed a tubular fold wherein is positioned a flexible rod 16 which may 85 be a straight cylindrical rod made from raw-hide or other like material as shown in Figure 4 or may have spaced peripheral grooves 17 formed in a rod 18 also of raw-hide or the like as in Figure 5. Another 90 form which this flexible rod may take is shown in Figure 7 wherein is disclosed a rod 19 formed of a square metallic wire spirally wound as in flexible shafting or the flexible temples used in spectacles.

95 The key holding units here disclosed each consists of a wire having one end wound to form a ring consisting of a convolution 20 from which projects a shank 21 which passes through a suitable opening in the eye 100 of a hook 22 and is provided with a head 23 to hold the ring and shank to the hook. These rings 20 engage on the flexible rod, being positioned in the grooves 17, when the form shown in Figure 5 is used, and the 105 shanks 21 project through the slots 14.

It is to be noted that the body 10, covers 11 and flap 13 are formed integrally from a sheet of suitable flexible material such as leather, a leather substitute or other like material.

In the form shown in Figure 8 there is

provided a body 24 having at one side a cover flap 25 which is foldable over on the face of the body, this flap and the body having cooperating snap button parts 26 by 5 which the cover may be held in closed position. At the other side of the body is a flap 27 which folds over the back of the body and is provided with an edge portion 28 which overlaps the folded part of the front cover 10 and may be secured thereto by cooperating snap button parts 29. At the top of the body is provided a rod holding flap 30 having spaced slots 31 formed therein, these slots being prolonged downwardly into the 15 body so that when the flap is doubled down the slots will extend downwardly an equal distance both in the body and the flap. This flap is held by the usual stitching 32. In this form it will be seen that the body, both 20 covers and flap are cut from a single sheet of material and form an integral whole as before.

The key hooks are held in this form just as in the first described form and these parts 25 have been accordingly given the same reference characters.

By reason of the slots extending downwardly both on the front and back of the body certain keys, such as those most used or 30 those which are expected to be used, may be positioned in front of the body while the remainder may be kept on the other side of the body. For instance one may keep his night latch key on one side and the remainder on the other or he may keep the keys to his automobile separate from other keys by a similar arrangement.

There has thus been provided a simple and efficient device of the kind described and for 40 the purpose specified.

Having thus described the invention, what is claimed as new, is:

1. A key case having a flexible body and covering means, a flexible flap forming an 45 extension of said body, said flap being provided with spaced slots and being secured adjacent its lower edge to the body, a flexible rod held within the flap and extending across the slots, and key holding units carried by said rod and projecting through said 50 slots, said slots extending into the body below the top thereof whereby the key holding units may be positioned against each side of the body, and key covering means carried by 55 the body and arranged to cover keys on both sides of the body.

2. A key case having a flexible body and covering means, a flexible flap forming an 60 extension of said body, said flap being provided with spaced slots and being secured adjacent its lower edge to the body, a flexible rod held within the flap and extending across the slots, key holding units carried by 65 said rod and projecting through said slots, said slots extending into the body below the top thereof whereby the key holding units may be positioned against each side of the body, and key covering means carried by 70 the body and arranged to cover keys on both sides of the body.

top thereof whereby the key holding units may be positioned against each side of the body, said covering means including a flap at one side of the body foldable on the front thereof, a second flap at the other side of the 75 body foldable on the back thereof, and independent securing means on the flaps and body for holding the flaps independently in closed position.

3. A key case having a flexible body and 80 covering means, a flexible flap forming an extension of said body, said flap being provided with spaced slots and being secured adjacent its lower edge to the body, a flexible rod held within the flap and extending 85 across the slots and provided with spaced annular grooves lying opposite the slots, and key holding units each including a ring engaging the rod in a groove thereof, a shank extending through the slot opposite said groove and a hook swiveled to the shank, said slots extending into the body below the top thereof whereby the key holding units may be positioned against each side of the 90 body, and key covering means carried by the body and arranged to cover keys on both sides of the body.

4. A key case having a flexible body and covering means, a flexible flap forming an 95 extension of said body, said flap being provided with spaced slots and being secured adjacent its lower edge to the body, a flexible rod held within the flap and extending across the slots and provided with spaced 100 annular grooves lying opposite the slots, key holding units each including a ring engaging the rod in a groove thereof, a shank extending through the slot opposite said groove and a hook swiveled to the shank, said slots extending into the body below the 105 top thereof whereby the key holding units may be positioned against each side of the body, and key covering means carried by 110 the body, said covering means including a flap at one side of the body foldable on the front thereof, a second flap at the other side of the body foldable on the back thereof, and independent securing means on the flaps and body for holding the flaps independently in closed position.

5. A key case having a flexible body and covering means, a flexible flap forming an 115 extension of said body, said flap being provided with spaced slots and being secured adjacent its lower edge to the body, a flexible rod held within the flap and extending 120 across the slots, key holding units carried by said rod and projecting through said slots, said slots extending into the body below the top thereof whereby the key holding units may be positioned against each side of the body, and key covering means carried by 125 the body, said covering means including a flap at one side of the body foldable on the front thereof, a second flap at the other side of the body foldable on the back thereof, and independent securing means on the flaps and 130

body for holding the flaps independently in closed position, the covering means, flap and body being made integrally from a sheet of suitable material.

- 5 6. A key case having a flexible body and covering means, a flexible flap forming an extension of said body, said flap being provided with spaced slots and being secured adjacent its lower edge to the body, a flexible rod held within the flap and extending across the slots and provided with spaced annular grooves lying opposite the slots, key holding units each including a ring engaging the rod in a groove thereof, a shank extending through the slot opposite said groove and a hook swiveled to the shank, said slots extending into the body below the top thereof whereby the key holding units may be positioned against each side of the
- 10
- 15

body, said covering means including a flap 20 at one side of the body foldable on the front thereof, a second flap at the other side of the body foldable on the back thereof, and independent securing means on the flaps and body for holding the flaps independently in 25 closed position, the covering means, flap and body being made integrally from a sheet of suitable material.

7. A key purse including a body, a cover flap adapted to cover one side of the body, 30 a second cover flap adapted to cover the remaining side of the body, and key holding means at one end arranged to permit movement of keys from position against one side of the body to lie against the other. 35

In testimony whereof I affix my signature.

CHARLES LORBER.
